(57) **CLAIM**

The ornamental design for a combined speaker and wireless charger as shown and described.

DESCRIPTION

FIG. 1 is a front side perspective view of a combined speaker and wireless charger showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front side perspective view thereof, shown the state where the handle is pulled up; and,

FIG. 9 is a rear, bottom side perspective view thereof.

The broken lines in the drawings depict portions of the combined speaker and wireless charger that form no part of the claimed design.
